United States Patent Office

Des. 206,180
Patented Nov. 8, 1966

206,180

COMBINED SPOTLAMP AND ROTATABLE COLOR BEACON

Charles P. Crawford, Room 822, 79 W. Monroe St.,
Chicago, Ill.

Filed Apr. 26, 1965, Ser. No. 84,960

Term of patent 3½ years

(Cl. D48—20)

FIG. 1

FIG. 2

FIG. 1 is a front elevational view of a combined spotlamp and rotatable color beacon showing my new design, the fragmentary representation of a support pipe being for purposes of illustration only; and

FIG. 2 is a bottom plan view thereon.

I claim:

The ornamental design for a combined spotlamp and rotatable color beacon, as shown and described.
